UNITED STATES PATENT OFFICE

94,311

DESIGN FOR A UNITED RUBBER WORKER'S FEDERAL LABOR UNION BADGE OR SIMI- LAR ARTICLE

Howard R. Lloyd, Akron, Ohio

Application March 28, 1934, Serial No. 51,207

Term of patent 3½ years

To all whom it may concern:

Be it known that I, Howard R. Lloyd, a citizen of the United States, residing at Akron, in the county of Summit and State of Ohio, have invented a new, original, and ornamental Design for a United Rubber Worker's Federal Labor Union Badge or Similar Article, of which the following is a specification, reference being had to the accompanying drawing, forming a part thereof.

Figure 1 is a plan view of a badge or similar article showing my new design, and,

I claim:

The ornamental design for a United Rubber Worker's Federal Labor Union badge or similar article as shown.

HOWARD R. LLOYD.
